UNITED STATES PATENT OFFICE.

BENJAMIN H. COOPER AND THOMAS O. HENRY, OF TERRE HAUTE, INDIANA, ASSIGNEES TO COOPER & HENRY FOUNDRY CO., OF TERRE HAUTE, INDIANA, A PARTNERSHIP.

SASH-WEIGHT-MOLDING APPARATUS.

No. 921,640. Specification of Letters Patent. Patented May 11, 1909.

Application filed December 16, 1908. Serial No. 467,754.

To all whom it may concern:

Be it known that we, BENJAMIN H. COOPER and THOMAS O. HENRY, citizens of the United States, residing at Terre Haute, in the county of Vigo and State of Indiana, have invented certain new and useful Improvements in Sash-Weight-Molding Apparatus, of which the following is a specification.

10 The principal object of our present invention is to produce sash weights of a superior quality with a minimum of labor.

15 A further object is to produce weights of any desired length by means of the same pattern or mold.

20 These objects are accomplished by means of an improved molding apparatus embodying certain novel features which will be hereinafter more particularly described and claimed.

25 Referring to the accompanying drawings, which are made a part hereof, and on which similar reference characters indicate similar parts, Figure 1 is a central vertical sectional

30 view of a mold after the same has been prepared ready to receive the molten metal where the molding has been done by means of our present invention; Fig. 2 is a similar view of the pattern flask and combined stripping and sprue-pattern plate just after the sand has been introduced,—the last mentioned plate being adjusted to one of its several positions in order that one particular length of window weight may be produced,

35 and the same being shown in connection with a machine for mechanically packing the sand around the molds; Fig. 3 a sectional view of the cope after the sand has been packed but before the cope plate has been removed; Fig.

40 4 a plan of the pattern plate with a portion of the patterns attached thereto, the position of the other patterns being indicated by means of dotted lines; Fig. 5 a plan of the stripping and sprue-pattern plate; Fig. 6 a

45 plan of the cope pattern plate with the positions of a portion of the number-plate patterns indicated by means of dotted lines; Fig. 7 a perspective view of one of the finished weights, and Fig. 8 an end elevation,

50 showing the number indicating the weight.

In my improved means of molding sash weights the flask, in condition for use, consists (as is best shown in Fig. 1) of a main portion of drag 21, a cope 22 and a plain bottom plate 23. These are secured together

by means of clamps 24 and 25. The molten metal is poured in through the central opening or gate 26 in the cope, and flows laterally in all directions through the distributing sprue channels or gates 27 left in the top 60 of the main body of sand in the drag by the gate or sprue-patterns forming part of or affixed to the proper side of the stripping plate (as will be presently described) into the mold opening 28 left by the weight patterns. The molds proper (being plain cylindrical structures) leave smooth round openings in the sand, and the resulting weights, therefore, are without fins or any rough protuberances, as will be readily understood. Said weights instead of having eyes cast therein by means of cores, in the ordinary manner, have wire eyes, *e*, which are placed in the ends of the molds prior to the molding operation, and are left thereby 70 in the sand, where the molten metal will come in contact with and surround the shanks thereof, as will be presently more fully described.

In the molding of these sash weights the 80 drag or main portion of the flask is placed with its upper side downward and rests upon the combined stripping plate and sprue or gate mold 31, being held in accurate relation thereto by means of pins 32 on 85 shanks of the eyes *e* are then placed in perforations in ears 21' on said main portion of the flask, and keys 32' which pass through said pins above said ears.

The pattern plate 41 bearing the desired 90 number of weight patterns 42 (fifty-eight such patterns are shown in the construction illustrated) is placed below said stripping plate, with the patterns projecting up through holes in said plate into the chamber 95 within the walls of the flask. These weight patterns are made of a length sufficiently great to produce the longest and heaviest weights desired. The particular length and weight desired at the time is then secured 100 by interposing between the pattern plate and the stripping plate distance blocks 43 of a diameter equal to the difference between the length of the patterns and the length of weight which it is desired to produce. The 105 shanks of the eyes *e* are then placed in perforations in the free ends of the weight patterns 42, into which they fit with a suitable degree of looseness, and the sand is then packed around the molds until the side walls 110

of the flask are filled level full. The mold plate and molds are then withdrawn, leaving the eyes *e* in the extremities of the mold cavities, and the drag or main portion of 5 the flask is reversed in position and permitted to rest upon the bottom plate 23, to which it is firmly secured, as by clamps 24. The cope having previously (by means of the cope pattern plate 51 and the number 10 patterns 52) been suitably molded, is placed up on and secured to the drag, as by clamps 25, as is best shown in Fig. 1, and the weights are molded as previously stated. As 15 will be readily seen, the eyes *e* being ordinary screw-eye blanks, no cores are required or used in this operation, and the mold patterns being firmly secured to the mold pattern plate are held rigidly in proper position. As will be seen by an inspection of 20 the plan of the combined stripping plate and gate or sprue pattern, the holes in said plate through which the patterns pass intersect the sprue patterns in such a manner as to insure a proper distribution of the 25 molten metal during the process of molding. The result is that the molding is very rapidly and easily performed, and results in the production of a large number of weights at each operation, of any desired 30 length, and of unusual uniformity and smoothness. This is one of the sorts of molding where there is great advantage in the use of a mechanical tamper for packing the sand about the patterns. Owing to the very 35 great amount of friction between the patterns and the sand, due to the very large number of patterns employed, it is also desirable to provide mechanical means for withdrawing the patterns from the sand 40 after the tamping or molding operation has been completed.

Referring now especially to Fig. 2, we have illustrated an air cylinder 61 containing a piston 62, below which is an air inlet 45 63 communicating with a line of pipe 64 leading from a suitable source of air supply, (as an air compressor) not shown. This air inlet is controlled by a valve 65. A very short distance above the air inlet we provide an opening or openings 66 through 50 which the air may escape, and which preferably enters a chamber 67, which is provided at one point with an escape pipe 68, leading to the open air, which is controlled by a valve 69. When the valve 69 is open, and the air pressure is turned on by the 55 opening of valve 65, the result is a very rapid reciprocation of the piston to which the mold is attached; and the sand (being allowed to run into the flask gradually) is, 60 by this constant reciprocation and jarring, evenly and firmly packed about the weight patterns. When the flask is properly filled, the valve 69 is closed, and the complete 65 flask (containing the patterns and sand) is

elevated by the air pressure to the position shown by the full lines in Fig. 2. The flask is then swung around slightly so that the ears 31' on stripping plate 31 rest on the top of columns 60, thereby supporting the 70 weight of the flask by said columns. The keys 32' are then removed. The air pipe 64 has a branch which leads to the upper end 75 of cylinder 61 which contains a valve 71. There is also an outlet pipe 72 at or near the upper end of the cylinder containing valve 73. The valve 73, which has been left open during the operations up to this point, is now closed, and the valve 71 and also the valve 69 are opened. Air pressure is thus 80 applied to the upper side of piston 62, which is thus operated to draw pattern plate 41 and patterns 42 downwardly, thus withdrawing the patterns through stripping plate 31 from the flask, ready to receive 85 either the same or another flask body for repetition of the operation.

The flask in which the molding operation is completed is then transported to a suitable place for the molding operation, which 90 may be conveniently done by swinging it from a crane by means of its gudgeons 21'', and the parts are then brought into the relations shown in Fig. 1, ready for the casting 95 operation.

Having thus fully described my said invention, what we claim as new, and desire to secure by Letters Patent, is,

1. The combination, in a sash weight mold, of a body flask, a combined stripping 100 and sprue pattern plate, and a pattern consisting of a plate having a plurality of weight patterns attached thereto, said stripping and sprue-pattern plate resting on and supported by the plate of said pattern during the molding operation, and having holes registering with the weight patterns and through which said weight patterns extend during the molding operation.

2. The combination, in a sash weight mold, of a flask body, a pattern plate carrying a plurality of weight patterns, and a combined stripping and sprue-pattern plate having holes through which the weight patterns extend and interposed between the pattern plate and the flask body, and arranged to rest upon the pattern plate during the molding operation.

3. The combination, in a sash weight mold, of a flask body, a pattern plate carrying a plurality of weight patterns, a combined stripping and sprue-pattern plate through which the weight patterns extend, a cope body, and a cope pattern plate bearing removable patterns for indicating the weight 120 of the castings, the mold-depressions in the sand of the cope being thus beyond the sprue cavities in the sand of the drag.

4. The combination, in a sash weight molding apparatus, with the flask contain- 130

ing the molds, of a stripping plate secured to the under side of said flask, a pattern plate carrying patterns arranged below said stripping plate with the patterns extending up through the holes in said stripping plate into said flask, and a piston and cylinder arranged below said pattern plate and secured thereto, whereby the complete flask is first raised to a considerable height, there secured, and then by a reversal of the pressure 10 the pattern plate carrying the weight patterns is withdrawn from the flask.

5. The combination, in a sash weight mold, of a flask, patterns of the general form of the weights to be produced and provided with eye-receiving orifices in their in- 15

ner ends and adapted to extend longitudinally into the sand within the flask, and a stripping plate through which said patterns extend and through which they may be withdrawn leaving the eyes carried by said eye-receiving orifices within the mold cavities. 20

In witness whereof, we have hereunto set our hands and seals at Terre Haute, Indiana, this twelfth day of December, A. D. 25 one thousand nine hundred and eight.
